ACHILL BIPPART, OF NEWARK, NEW JERSEY.

LINK-BUTTON.

1,148,821.

Specification of Letters Patent.

Patented Aug. 3, 1915.

Application filed April 24, 1914. Serial No. 834,052.

To all whom it may concern:

Be it known that I, ACHILL BIPPART, a citizen of the United States, residing at 788 South Tenth street, Newark, county of Essex, and State of New Jersey, have invented 5 certain new and useful Improvements in Link-Buttons, fully described and represented in the following specification and the accompanying drawings, forming a part 10 of the same.

The object of this invention is to furnish a link-button in which the link shall be jointed to loops upon both heads of the button and shall lie close to their inner sides 15 to facilitate the passage of the button-heads through the buttonholes, and the link also operates to crowd the linen toward the button-heads, and to limit the tipping movement of the heads upon the link when inserted in the cuff. These objects are attained by forming the button-heads with loops lying close to their inner surfaces and forming the link with relatively broad side-bars, and ends materially thinner than such 25 side-bars with inclined shoulders upon the side-bars adjacent to such ends, which shoulders serve in practice to crowd the linen toward the button-heads.

The cross-bars are preferably made materially longer than the width of the loop 30 so that the button-heads may slide on the cross-bars and connect with the link in an inclined position near either side-bar.

The junction of the side-bars and cross-bars are formed with exterior corners to contact with the inner sides of the button-heads, so that when the loops on the button-heads are adjacent to either side-bar and the button-heads inserted in the cuff, the inclination or tipping of the button-heads is limited, to incline the button-heads parallel with the oppositely sloped surfaces of the cuff.

The invention will be understood by reference to the annexed drawing, in which—

Figure 1 is a section of the cuff-wings lengthwise of the button-holes with the cuff-button inserted therein; Fig. 2 is a section of the cuff-wings transverse to the button-holes with the cuff-button therein; Fig. 3 shows the inner side of the link-button when in readiness for insertion in the buttonhole; and Fig. 4 is an edge view of the button-heads and link in the same position.

Each of the heads α is shown with a loop or staple b upon its inner side, and the link

is formed with side-bars c of much greater breadth than the thickness of the cross-bar d , with sloping shoulders e near the point where they are joined to the cross-bars, so that when the button is inserted in the buttonhole f the linen lying across the ends of the side-bars is crowded toward the heads by such sloping shoulders, as shown in Fig. 2. The side-bars are of uniform breadth 60 between the shoulders e to facilitate their easy passage through the button-holes, and Fig. 4 shows how the reduction in breadth of the side-bars at their ends and the corresponding reduction in the height of the 70 loops enables the edges of the side-bars to lie substantially even with the tops of the loops, so that all of the parts slip through the buttonholes with equal ease.

The cross-bars are preferably made materially longer than the width of the loops, as is clearly indicated in Figs. 1 and 3, which permits the loops upon the button-heads to slide upon the cross-bars into contact with either of the side-bars, and when in such position to be inclined toward each other, as shown in Fig. 1. Either side-bar of the link may thus be placed in the forward edge of the button-holes and either edge of the button-heads may thus be brought next to 75 the edges of the cuffs where they are most exposed to wear. The incline of the button-heads, when the loops are at the ends of straight side-bars, would be impossible if the loop held the cross-bar snugly against 80 the button-head, but such snug adjustment is desirable to avoid as much as possible a projection of the loop upon the inner side of the head, so that the loops may project little, if any, beyond the edges of the side-bars when inserting them through the button-holes.

My construction, which is clearly shown in Fig. 4, permits the insertion of the head α into the button-holes without any material 100 obstruction, and I have constructed the end of my link with special reference to this low form of loop and the necessity for tipping at the ends of the cross-bar, and this tipping I effect by arching the middle of the cross-bar outwardly which produces a backward sloping of the cross-bar at its junction with the side-bars; such sloping being nearly the same as that naturally assumed by the button-head when fitted to the cuff, as shown 105 110 in Fig. 1.

The links are symmetrical in form, and

the ends of the cross-bars, where joined to the side-bars, form corners e' which contact with the inner side of the button-head near the edge of the loop, and prevent the button-head from rocking upon the end of the link beyond a certain angle which is shown in Fig. 1, and corresponds with the slope that the wings g of the cuff ordinarily assume when confined by the cuff-button.

10 The present improvements greatly facilitate the passage of the button-heads through the buttonholes, while operating to press the cuff-wings toward the button-heads, and also to permit either edge of the button-heads to be projected forwardly upon the cuffs, and these improvements are effected by modifications of the construction which do not materially increase the cost, and thus secure a great advantage without increased 20 expense.

Having thus set forth the nature of the invention what is claimed herein is:

The link-button herein described, with

two heads having each a low loop upon its inner side, a symmetrical open-bodied link 25 having relatively broad side-bars, and cross-bars fitted to the loops and arched outwardly and sloping backwardly at their ends, and each cross-bar being materially longer than the width of its loop and the 30 latter thereby enabled to slide thereon and tip at either end of its movement, the side-bars being provided each upon its edges with inclined shoulders adjacent to their ends sloped toward the cross-bars, and the 35 link having corners at the ends of both side-bars, to limit the angular movement of the heads when set at either corner of the loop.

In testimony whereof I have hereunto set 40 my hand in the presence of two subscribing witnesses.

ACHILL BIPPART.
